UNITED STATES PATENT OFFICE.

JOHANN MARTIN LASSMAN, OF TAGANROG, RUSSIA.

LUBRICATING DEVICE FOR JOURNAL-BOXES.

1,104,361.

Specification of Letters Patent. Patented July 21, 1914.

Application filed March 8, 1912. Serial No. 682,560.

To all whom it may concern:

Be it known that I, JOHANN MARTIN LASSMAN, a subject of the Emperor of Russia, residing at 45 Greece street, Taganrog, in the Empire of Russia, have invented certain new and useful Improvements in Lubricating Devices for Journal-Boxes, of which the following is a specification.

The present invention relates to a special 10 method of automatically supplying lubricant from below to axle ends and also to the construction of an axle box for this purpose, and is characterized by the fact that the lubricant is supplied from below to the axle 15 box by means of a piston pump arranged inside the box and operated by means of a crank which is arranged on the extremity of the axle end.

An axle box embodying the invention is 20 illustrated by way of example in the accompanying drawing, in which:

Figure 1 is a longitudinal section of the box on the line A—B in Fig. 2. Fig. 2 is a front elevation and section on the line C—D 25 in Fig. 1.

The lubricating device consists of a box 9 with removable cover 10 provided with the parts of a piston pump and with a lubricating cup. The entire lubricating device is 30 readily removable for the purpose of examining and cleaning the axle box. The lubricant box 9 arranged in the axle box with its partitions 10' and 11 and the openings 9' facilitates the separation of the oil from 35 any admixtures present. The lubricant is poured in through the front cover of the axle box until the lubricant box 9 is covered. The oil reaches the lower part of the lubricant box, runs down onto the bottom of 40 the axle box 10', fills the space between the box 9 and the axle box, reaches the hole 9', and passes into the interior of the lubricant box from which it passes under the projection 11 from the cover of the lubricant box 45 and over the partition 10' into the chamber 12 of the pump reservoir and gradually fills 50 the entire box. On its way the oil separates from the admixtures of higher specific gravity and when it enters the pump chamber it is already purified. The oil required 55 for lubricating is supplied from the chamber 12 by the pump during the running of the train; this pump is driven by the rotating axle. With this object the pump piston 13 is mounted on a pin 14 which is eccentric relatively to the axis of the axle. The move-

ment of the piston causes the oil to pass through the ball valve 15 beneath the piston of the pump and thereupon in the downward movement of the piston oil is forced 60 through the passage 16 and the ball valve 17 into the cup 18 which is applied to the axle by the spring 19 so that the oil flows over the lower part of the axle end and adheres to its surface, lubricates the bearing and 65 flows back to the pump chamber along the path described becoming separated from water, metal, sand and the like on its way. The oil supplied collects on the periphery of the axle and is thrown off in all directions by the rotary movement of the axle. 70 A portion of the oil passes beneath the part 20 and as it runs along the nose 21 it also lubricates the pin 14 and the pump piston 13.

What I claim and desire to secure by Letters Patent of the United States is:—

1. In combination, an axle, an axle box, a lubricant receptacle contained in said axle box, a cover for said receptacle, a pump chamber in communication with said receptacle, means formed by said receptacle and said cover to prevent foreign matter from passing with the lubricant into said pump chamber, a pump in said pump chamber and means to operate positively the said pump 80 from said axle to force the lubricant steadily from said receptacle onto said axle.

2. In combination, an axle, an axle box, a lubricant receptacle contained in said axle box and having an inlet for the lubricant, a 90 cover for said receptacle, a pump chamber in communication with said receptacle, means formed by said receptacle and said cover to prevent foreign admixtures from passing along with the lubricant into said 95 pump chamber, a pump in said pump chamber, a delivery funnel, means to hold said funnel in resilient contact with said axle, and means to operate said pump positively from said axle to discharge the lubricant 100 steadily from said receptacle through said funnel onto the axle.

3. In combination, an axle, an axle box, a reservoir for containing lubricant located in said axle box, a cover for said reservoir formed with a channel, a pump chamber communicating with said reservoir and with said channel at one end of the latter, a ball valve to interrupt the flow of lubricant from said reservoir into said channel, a delivery 110 funnel located at the other end of said channel, a ball valve in the neck of said funnel,

a pump in said pump chamber, and driving means connected with and eccentrically disposed relatively to said axle to operate said pump to force the lubricant from the reservoir past the first mentioned ball valve, along said channel, past the second mentioned ball valve into said funnel, thence onto the axle.

4. In combination, an axle, an axle box, a reservoir for containing lubricant disposed in said axle box, a readily removable reservoir cover comprising a pump chamber and a lubricant delivery funnel both in communication with said reservoir, the said pump chamber and the neck of said delivery funnel being both formed as one piece, a pump arranged in said pump chamber and means to operate said pump positively from said axle to force the lubricant steadily from said reservoir through said funnel onto said axle.

In testimony whereof I affix my signature in presence of two witnesses.

JOHANN MARTIN LASSMAN.
